(57) **CLAIM**

The ornamental design for a surface pattern for use on furniture, as shown and described.

DESCRIPTION

FIG. 1 is a top plan view of a surface pattern for use on furniture, showing my new design embodied in a stool:

FIG. 2 is a perspective view thereof;

FIG. 3 is a perspective view of a surface pattern for use on furniture, shown embodied in a chair; and,

FIG. 4 is a top plan view of the seat portion of the chair shown in FIG. 3.

The broken lines are for environmental purposes only and form no part of the claimed design.
